[57] CLAIM

The ornamental design for a barrel sign, as shown and
described.

DESCRIPTION

FIG. 1 is a perspective view of a barrel sign showing
my new design, with the broken lines shown for illustra-
tive purposes only and forming no part of the claimed
design;

FIG. 2 is a front elevational view thereof;

FIG. 3 is a top plan view thereof.

FIG. 1

FIG. 2

FIG. 3
